UNITED STATES PATENT OFFICE.

DELIA G. DOWLING, OF NEW YORK, N. Y.

DESIGN FOR A TRAY.

55,369.

Specification for Design.

Patented June 1, 1920.

Application filed November 22, 1919. Serial No. 339,955. Term of patent 7 years.

To all whom it may concern:

Be it known that I, DELIA G. DOWLING, a citizen of the United States, residing at New York city, in the county of New York and State of New York, have invented a new, original, and ornamental Design for Trays, of which the following is a specification, reference being had to the accompanying drawing, forming part thereof.

Figure 1 is a perspective view of the tray showing my design.

Fig. 2 is a side elevation of the same.

I claim:

The ornamental design for a tray, as shown.

In testimony whereof I hereunto affix my signature.

DELIA G. DOWLING.
